UNITED STATES PATENT OFFICE.

JOHN LLOYD ENYEART, OF SHIRLEYSBURG, PENNSYLVANIA.

WIRE-STRETCHER.

SPECIFICATION forming part of Letters Patent No. 398,596, dated February 26, 1889.

Application filed September 26, 1888. Serial No. 286,458. (No model.)

To all whom it may concern:

Be it known that I, JOHN LLOYD ENYEART, a citizen of the United States, residing at Shirleysburg, in the county of Huntingdon and 5 State of Pennsylvania, have invented a new and useful Improvement in Wire-Stretchers, of which the following is a specification.

My invention is an improvement in wire-stretchers; and it consists in certain novel features hereinafter described and claimed.

In the accompanying drawings, Figure 1 is a perspective view of my improved wire-stretcher, showing it in position on a fence-post. Fig. 2 is a plan view of the stretcher detached from the post. Fig. 3 is a vertical section on the line *x x* of Fig. 2.

Referring to the drawings by letter, A designates an L-shaped casting, having its shorter arm, B, curved slightly inward and rearward, 10 so as to form the point C at its extremity, as clearly shown in Fig. 2. On the upper side of the arm B, I form the lugs or ears D D, in which the driving-shaft E is journaled. The driving-shaft E is provided with a crank-handle, F, at one end, and between the lugs D D, I mount upon the shaft E the sprocket-wheel G and the ratchet-wheel H, as shown. The shaft, ratchet-wheel, and sprocket-wheel are 15 preferably formed in one entire piece for convenience in manufacture, as will be readily understood. On the under side of the arm B, I secure an eye, I, in which is hinged a pawl, J, as shown. This pawl consists of a wire bail or loop having its ends secured in the eye, 20 thence extending forward under the casting, and then upward past the same, as shown, the upper end of the pawl engaging the teeth of the ratchet-wheel H, to prevent retrograde movement of the driving-shaft. The sprocket- 25 wheel is engaged by a sprocket-chain, K, as shown, to the end of which is secured the wire-clamp L. The sprocket-wheel is of such a diameter that the lowest point of its circumference is very near the upper side of the casting, so that the chain can pass between the 30 wheel and the casting only when the wheel is rotated, and the links of the chain are engaged by the teeth of the wheel. The end of the chain passes downward between the post and the shorter arm of the casting, as shown 35 in Fig. 1.

The clamp L consists of the pawl or cam M, secured to the end of the chain, the body N, pivoted to the end of the cam, and the keeper-plate O, pivoted to the opposite side of the 55 cam and adapted to pass beyond the edge of the body N, to prevent the wire from slipping between said body and the cam.

A securing-chain, P, is permanently attached to the end of the longer arm of the 60 casting A, and is adapted to be passed around the post and engage a hook, Q, on the end of the shorter arm of the casting, thereby securing the same to the fence-post, as will be readily understood.

In practice the casting A is secured to the fence-post in the manner just described by passing the chain P around the fence-post, the clamp L is caused to engage the end of the wire, and the chain K is passed under the 70 sprocket-wheel G, after which the driving-shaft is rotated, thereby drawing the clamp L and the wire held thereby toward the post, consequently stretching the wire, as will be readily understood. After the wire has been 75 stretched to the desired degree the pawl J is caused to engage the ratchet-wheel, so as to prevent backward rotation of the driving-shaft and consequent slackening of the wire. It will be understood that the tension of the 80 wire is exerted against the end of the pawl through the ratchet-wheel, and the pawl and wheel thereby caused to bind against each other, so that the pawl will be prevented from falling and the wheel prevented from rotating. The pawl can be constructed so as to automatically engage the ratchet-wheel at all 85 times by giving it a spring temper, and the same result will be accomplished by inverting the device.

It will be seen that I provide a very simple and efficient wire-stretcher, by means of which the wire can be quickly and rapidly stretched to the desired degree. By having the shorter arm of the casting A curved, as shown, and 90 provided with the point C, the main portion of said arm is held away from the fence-post, so as to allow ample room for the rotation of the sprocket and ratchet wheels. The point C also is caused to embed itself in the side of 95 the post by drawing the securing-chain 100 tightly around the post, so that the casting

will be firmly held in position. The longer arm of the casting has a flat inner side, which bears against the side of the post, and thereby prevents wobbling of the device, as will be readily understood. The clamp receives the fence-wire between the body N and the cam M, and when the driving-shaft is rotated the pull exerted thereby on the chain K draws the cam firmly against the wire, thereby clamping it against the body, so that it will not slip. The keeper-plate O is extended past the edge of the body, so as to prevent the wire from slipping laterally therefrom, as will be readily understood upon reference to the drawings.

15 The longer arm of the casting is provided with a clamp, R, similar in construction to the clamp L, for use in splicing broken wires or connecting the ends of sections of the wire.

20 The manner of using the device in splicing will be readily understood upon reference to Fig. 2. The end of one section of the wire is secured in the clamp R, and the end of the other section is secured in the clamp L. The spur-wheel is then rotated, as will be understood, to draw the ends of the two sections of the wire together, and the meeting ends twisted around each other, completing the splice.

25 Having thus described my invention, what I claim, and desire to secure by Letters Patent, is—

1. The combination of the casting A, the driving-shaft mounted thereon having a ratchet-wheel, the eye secured to the under side of the casting, and a pawl secured in said eye 35 and extending around the casting and engaging the teeth of the ratchet-wheel, as set forth.

2. The improved wire-stretcher comprising the L-shaped casting A, having the lugs D D on the upper side of its shorter arm and the hook Q at the end of said arm, the chain permanently attached to the end of the longer arm of the casting and adapted to engage the end of the hook Q, the driving-shaft journaled in the ends of the lugs D D, the sprocket and ratchet wheels mounted on the said shaft between said lugs, the chain passing beneath and engaging the sprocket-wheel, the clamp at the end of the chain, and the pawl secured to the under side of the casting and engaging 45 the teeth of the ratchet-wheel, substantially as specified.

40 In testimony that I claim the foregoing as my own I have hereto affixed my signature in presence of two witnesses.

JOHN LLOYD ENYEART.
